(57) **ABSTRACT**

An upright piano main action rail with a special cross sectional shape of its lower half that angles or curves towards the back of the piano to effectively relocate the lower front surface of upright piano main action rail from a position in front of the row of whippens as with the prior art to a relocated new position behind the row of whippens flanges to enable the front mounting of whippens flanges to the main action rail. Upright piano main action rail has all whippens mounting holes located its the lower front surface instead of the lower rear surface as with prior art upright piano main action rails.

**MAIN ACTION RAIL FOR UPRIGHT PIANO
WITH FRONT-ACCESSIBLE WHIPPEN
FLANGE SCREW**

BACKGROUND OF THE INVENTION

1. Field of the Invention

This invention relates to upright piano actions, or more specifically the mechanisms in upright pianos that transmit motion from a piano player's fingers into motion of a hammer, located inside the piano, causing the hammer to strike a piano string, thereby producing sound or music from the piano. In every piano, there is a separate piano action and hammer corresponding to each piano key, where there are typically 88 keys in a piano. All piano actions and the hammers must be fastened to a stationary "rail" inside the piano in order to allow for proper motion of the piano action's sub-components and cycling of the piano action. There is more than one rail in an upright piano, including the damper spring rail, the hammer rail, the main action rail, the let-off rail, the sticker rail, capstan rail, the balance rail, and the front rail. Typically, all rails run horizontally across the width of the piano, parallel to the row of piano keys on the piano. This invention deals with the "main action rail" of an upright piano.

2. Description of Related Art

Prior art main action rails for upright pianos include a design with whippens and flanges located on the rear or back of the piano action, where rear or back is defined as the side opposite the piano keys. With prior art main actions rails, the whippens and flanges are only accessible from the rear of the piano.

This poses a huge problem for piano technicians for logistical reasons because a great deal of work is required to gain access to the whippens and flanges located at the rear of the piano action. Periodically, for proper maintenance of the piano, replacement or repair of piano action subcomponents is required, thereby requiring the removal of whippens and flanges from the piano.

To remedy this, the main action rail for upright piano of this invention includes a design with the whippens and flanges located on the front of the main action rail, thereby providing front-access to all whippens and flanges, thereby greatly reducing the work required for technicians to remove the whippens and flanges.

BRIEF SUMMARY OF THE INVENTION

It is an aspect of this invention to provide a main action rail for an upright piano with front-mountable whippens and flanges.

It is an aspect of this invention to provide a main action rail for an upright piano with a "lower-front surface" that is located behind the "lower-rear surface" of prior art main action rails for upright pianos.

It is an aspect of this invention to provide a main action rail for an upright piano with a thinner cross-sectional design as compared to that in the prior art.

It is an aspect of this invention to provide a main action rail for an upright piano where the tapped holes for mounting the whippens and flanges are located on the "front" surface of the main action rail and not on the "rear" surface of the main action rail.

It is an aspect of this invention to provide a main action rail for an upright piano with design that provides the ability to install all whippens and flanges from the front of the piano action where the hinge pin or center pin in each whippens and flanges

2

remains in the exact same location as those hinge or center pins in whippens and flanges attached to prior art main action rails.

BRIEF DESCRIPTION OF THE DRAWINGS

5 FIG. 1 is a right rear perspective view of a prior art main action rail depicting a whippens and flanges just prior to insertion of the whippens and flanges into a whippens and flanges mounting hole located on the rear of the main action rail and blow-up thereof.

10 FIG. 2 is a left rear perspective view of a prior art main action rail depicting a whippens and flanges just prior to insertion of the whippens and flanges into a whippens and flanges mounting hole located on the rear of the main action rail and blow-up thereof.

15 FIG. 3 is a right front perspective view of main action rail for upright piano with front-accessible whippens and flanges depicting a whippens and flanges after installation of the whippens and flanges into a whippens and flanges mounting hole located on the front of the main action rail and blow-up thereof.

20 FIG. 4 is a left front perspective view of main action rail for upright piano with front-accessible whippens and flanges depicting a whippens and flanges after installation of the whippens and flanges into a whippens and flanges mounting hole located on the front of the main action rail and blow-up thereof.

25 FIG. 5 is a cross sectional view of a prior art main action rail and a cross sectional view of a main action with front-accessible whippens and flanges with the two cross sectional views in vertical alignment with each other depicting how the whippens and flanges center pin or hinge pin and the whippens and flanges remain in the exact same location for each design, while, on the other hand, the whippens and flanges are reversed by 180 degrees with the new design.

16	Front of Piano Action

DETAILED DESCRIPTION OF THE INVENTION

FIGS. 1 and 2 depict a prior art main action rail 1 for an upright piano. A main action rail is a stationary rail running horizontally across the entire width of the piano keys of the upright piano. All 88 whippens 7 and 88 whippens and flanges 5 must be affixed or adhered to the main action rail 1. FIGS. 1 and 2 depict cut-away views of the main action rail 1, showing just one of the 88 piano actions and whippens and flanges of the piano. Depictions of main action rails 1 in FIGS. 1 and 2 are cut-away views of the full width of the main action rail 1.

Prior art main action rails **1** for upright pianos include a design where the tapped holes or mounting holes for the whippens flange are located on the rear or back **8** of the main action rail **1**.

This poses a huge problem for piano technicians for logistical reasons because a great deal of work is required to gain access to the whippens flange screw **3** located at the rear of the piano action **8**. Periodically, for proper maintenance of the piano, replacement or repair of piano action subcomponents is required, thereby requiring the removal of whippens **7** and whippens flanges **5** from the piano.

To remedy this, main action rail for upright pianos with front-accessible whippens flange screws **9** includes a design with location of the whippens mounting holes on the front of the main action rail **9**, thereby providing front-access to all whippens flange screws **11**, thereby greatly reducing the work required for technicians to remove the whippens flange **13** and whippens **15**.

This is accomplished by the re-design of the cross-section of main action rail for upright pianos with front-accessible whippens flange screws **9**. As can be seen from a comparison between FIGS. 1 and 3, we see that, in FIG. 3, with the new rail **9**, the front surface of the new rail **9**, into which whippens flange screw **11** is installed, has been “set-back” or moved backwards, as compared to the corresponding front surface of prior art rail **1** in FIG. 1. (Note that FIG. 1 depicts a back-view of the action, while FIG. 3 depicts a front-view of the action, so we must compare the surface depicted in FIG. 3 to the surface not depicted in FIG. 1.)

The location of each whippens flange **5** and **13** in each of FIGS. 1 and 3 remains constant, so that, in relation to the other action components, whippens flange **5** has the exact same location as whippens **13**. More precisely, hinge pin **6** has the exact same location as hinge pin **14**. The only difference in the flanges is that whippens flange **5** uses a whippens flange screw **3** entering from the rear **8**, while whippens flange **13** uses a whippens flange screw **11** entering from the front **16**. This aspect provides the ability for main action rail for upright pianos with front-accessible whippens flange screws **9** to be compatible with prior art piano action components.

To accomplish this, main action rail **9** must have a special cross-sectional profile that is best described by FIG. 5. The top of FIG. 5 depicts a perpendicular lateral cross section of prior art main action rail **1** at a point that is the longitudinal bisection of a whippens flange **5**. Commensurately, the bottom of FIG. 5 depicts a perpendicular lateral cross section of new main action rail **9** at a point that is the longitudinal bisection of a whippens flange **13**. The purpose of the top/bottom comparison of the two designs is to more visually describe the differences in cross sectional shapes of the two main action rails **1**, **9**. Line **19** is a vertical line depicting how whippens flange **5**, along with its center pin or hinge pin **6**, as attached to the prior art main action rail **1**, remains in the exact same location relative to all other components of the piano action as whippens flange **13**, along with its center pin or hinge pin **14**, as attached to the new main action rail **9**, with the new main action rail installed as a new improved replacement main action rail for the upright piano. This aspect is required for proper piano functioning of the new main action rail **9** in the piano.

The right side of FIG. 5 is the front of the piano as designated by item **16**. The left side of FIG. 5 is the back or rear of the piano as designated by item **8**. With this in mind, examining the top/bottom comparison of the two designs in FIG. 5, it is depicted how the new design uses a “front” attachment whippens flange screw **11**, while the old design uses “rear” attachment whippens flange screw **3**.

A main reason why the new design may incorporate “front” attachment whippens flange screws **11** is because of a void or clearance space **20**. With the new design, just below the hammer butt flange **17**, main action rail **9** does not extend straight downward with a relatively large mass of material positioned in front of whippens flange **5**, as does main action rail **1**, but rather angles or curves towards the rear of the piano, to then drop downward with a relatively thin mass of material **21** behind whippens flange **13**. Mass of material **21** has thickness that is about half that of prior art main action rail **1**. Whippens flange **13** remains in the exact same position as whippens flange **5** as between new and old designs. Clearance space **20** is required to allow a piano technician access to front attachment whippens flange screws **11**.

This new cross sectional shape of main action rail **9** also provides a mass of material or solid portion **21** that does not exist with main action rail **1**. Mass of material **21** of main action rail **9** extends behind whippens flange **13**. Portion **21** is required to provide anchor points for the front attachment of whippens flanges **13** by whippens flange screws **11** because this portion must contain a row of tapped holes where each is used to secure a whippens flange screw **11** to yield front access capability for a piano technician.

What is claimed is:

1. A main action rail for an upright piano, wherein said main action rail is a stationary rail running horizontally across the width of said upright piano, said main action rail comprising an upper half with a front and rear surface and a lower half with a front and rear surface, said upright piano comprising a front side, a rear side, a plurality of hammer butt flanges, each attached to said upper half of said main action rail to yield a horizontal row of hammer butt flanges running parallel to said main action rail, and a plurality of whippens flanges, each attached to said lower half of said main action rail to yield a horizontal row of whippens flanges running parallel to said main action rail, each of said whippens flanges comprising a front surface and a rear surface and said horizontal row of whippens flanges comprising a front side and rear side, and said main action rail has a special cross-sectional shape so that the rear surface of said upper half of said main action rail is located on said front side of said horizontal row of whippens flanges and said front surface of said lower half of said main action rail is located on said rear side of said horizontal row of whippens flanges, thereby offsetting said lower half of said main action rail to said rear side of said horizontal row of whippens flanges, to provide a mass of material on said rear side of said horizontal row of whippens flanges and a void or clearance space on said front side of said horizontal row of whippens flanges below said horizontal row of hammer butt flanges.
